UNITED STATES PATENT OFFICE.

EDWIN CLARK, OF CHICAGO, ILLINOIS.

CORN HUSKER.

1,410,091.

Specification of Letters Patent. Patented Mar. 21, 1922.

Application filed June 20, 1918. Serial No. 241,012.

To all whom it may concern:

Be it known that I, EDWIN CLARK, a citizen of the United States, residing at Chicago, in the county of Cook and State of Illinois, have invented new and useful Improvements in Corn Huskers, of which the following is a specification.

The object of the invention is to provide an improved construction of corn husker and more especially of a device of that type embodying a husking pin and the means for carrying the same or attaching it operatively to the hand of the operator, and of securing the pin proper to the strap or other device constituting the fastening or holding means, to the end that the requisite strength and efficiency of the device may be secured at a minimum cost of manufacture and the utmost simplicity of construction, while insuring the ready adaptability of the apparatus to the hand of the operator and to the peculiarities of use by individual operators.

With these and similar objects in view, as will appear in the course of the following description, the illustrated embodiment, representing a preferred form, consists of a certain construction, combination and relation of parts, which, as will be understood, however, may be modified in form, proportion and details, within the scope of the appended claims, without departing from the spirit of the invention.

In the drawings:—

Figure 1 is a general view of the husker including thumb and finger stalls or cots and wrist band as seen when applied in proper position to the hand of an operator.

Figure 2 is a side view partly in section of the pin and finger stall with the connected strap showing the means whereby said elements are connected.

Figure 3 is a plan view of the same.

Figures 4 and 5 are detail transverse sectional views on the planes indicated by the lines 4—4 and 5—5 respectively of Figure 3.

Figure 6 is a top plan view of the husking pin.

Figure 7 is a plan view of the wrist-band.

Figure 8 is a perspective view of the thumb cot and finger cot and their attendant connecting medium.

The husking pin 10 is constructed of sheet metal, of a suitable gage, rolled as at 11 to form a handle or grip with the side edges brought into proximity and relative paral-

lelism, it being preferable however, to allow said edges to remain separated to an extent sufficient to form an intermediate parallel sided space or slot which constitutes a convenient rest or grip for the finger tips to act as a further means of enabling the operator to prevent the turning of the rolled handle portion in the hand. Beyond the rolled portion the blank is broadened or flattened to an extent sufficient to form a concaved blade 12 terminating in a relatively sharp point 13, and as a means of stiffening this blade portion of the pin it may be reversely curved as shown and up-struck or corrugated to form inwardly and outwardly projecting longitudinal rib portions 14 and 15 and diagonally disposed rib portions 16. The concave relatively flattened and broadened portion of the blade forms a suitable bearing for the thumb of the operator without involving such abrasion as would constitute an inconvenience in long continued use of the pin.

In connection herewith there is used a strap 17, substantially of the form now in use which is permanently secured near one end, as for example the buckle end 18, by means of a rivet 19, the inner end of which is located within the rolled handle so as to be out of reach and thus removed from contact with the hand of the operator. Also the said strap has a running engagement with the pin by means of rings 20 and 21, each consisting as shown of a blank of wire of which the extremities are engaged with openings or perforations 22 formed in the sides of the rolled portion of the pin, the openings or perforations for each ring being disposed in staggered relation or slightly out of registration transversely so that the ends of the wire blanks inserted through said openings are out of alignment and pass each other to thus form an overlap. This facilitates the application of the ring to the pin by avoiding terminal contact, and at the same time insures a firm engagement of each end of the blank with the handle portion of the pin, while permitting a relative swinging movement of the ring to adapt itself to the movements of the strap and the position of the hand of the operator. The intermediate ring 20 also serves as a guide for the back-run of the strap, as shown at 17^a which is terminally engaged by the aforesaid buckle 18 providing for adjustment to suit the size of the hand of the operator, while the forward

ring 21, in addition to engaging the strap serves as a means for holding and properly positioning a finger stall 23 designed to engage the index or fore-finger of the operator. 5 Preferably the sides of the ring 21 are passed through independent perforations 24 in the leather or some other material constituting the finger stall or cot 23, so that provision is made against relative disengagement of the 10 parts in the use of the device. Also as shown in the drawings the finger stall may be armored or provided with metallic spurs or disks 25, secured thereto in any suitable or preferred manner.

15 In the construction illustrated there is connected with the finger stall, by means of an adjustable strap 26 a thumb stall 27 which may also be suitably armored, and said strap at an intermediate point has a 20 running engagement with a wrist-band 28 designed to be arranged in two wraps or folds around the wrist of the operator and having an elongated opening 29 through which the buckle 30 on the inner fold or 25 wrap projects for engagement with the extremity of the band. This provides for the necessary adjustment of the band to suit the size of the wrist and insures the exposure of the buckle, in order that the proper adjustment or tension of the band may be secured, while relieving the wrist from any pressure of the buckle and thus avoiding the inconvenience or irritation which might otherwise be produced thereby.

30 From the foregoing description it will be obvious that the required configuration of the pin may be secured, particularly with reference to the round handle or grip and the broad and relatively shallow blade or 35 bowl, together with the requisite strength and a minimum of weight which is unattainable in a solid pin or one which is formed from a solid rod or bar, without in any way sacrificing the convenience or comfort of the 40 operator or the security of the grip of the hand in the manipulation of the device. In addition however, to these advantages the attachment to the pin of the leather shield or strap is facilitated in the matter of manufacture both as to preparation and assembling, and in the matter of security and 45 hence durability of the tool, for the reason that the rivet at the rear end of the handle or grip portion of the pin is hollowed while 50 the rings which engage the shield or strap at an intermediate point have their extremities efficiently overlapped and housed within the cavity of the handle to avoid the possibility of accidental disengagement under 55 severe strain, said rings however being free to swing longitudinally of the pin in accordance with the positions of the engaging portions of the leather shield or strap, as previously noted. Obviously this relative freedom of movement of the rings serves to avoid 60

applying a transverse strain thereto, and hence minimizes the likelihood of such a distortion as would result in disengagement of the rings from the pin.

65 In addition to the advantage above given for the substantially tubular rolled form of the handle or grip portion of the pin, so that the side edges are brought in parallelism almost to a meeting relation,—namely to afford a rounded surface for the grip of the 70 hand (instead of half round or less with an opposite concave surface), said rounded surface being broken or interrupted only by a narrow slot to enable the operator to prevent twisting or turning of the tool in the hand, 75 there is a further and important purpose in so constructing the handle in view of the fact that it is desirable to use split rings, 80 easily applied and removed, as the means for providing a sliding connection between 85 the handle and the strap. A split ring exposed to strain is subject to a certain yielding movement, or expansion or enlargement, 90 within the range of elasticity of the wire of which it is formed (such enlargement becoming permanent if the strain exceeds the limit of elasticity) and also to a turning movement, or a movement parallel with the length of the wire relative to the handle, and either of these movements of the ring in connection with a hollow handle formed of a 95 sheet metal blank is liable to bring the split or opening at the terminals of the wire forming the ring into such relation with the handle as to cause disengagement of the ring 100 therefrom.

105 It is desirable to engage each ring, for greater security and strength, with two perforations or openings in a handle of the sheet metal type, and the substantially tubular form above described lends itself readily to this arrangement.

110 It is also desirable to protect the hand of the operator in grasping the handle, from contact with the rings, and particularly the terminals of the wire forming the rings, because said terminals are often uneven or sharp and are likely to chafe or injure the hand, and here again the substantially complete tubular form of the handle is important as a housing for the ends of the ring wire.

115 Moreover, it is desirable that the tendency of the ring under strain to permit separation of its terminals be prevented and therefore the ends are overlapped, so that a considerable expansion is possible without such separation; and furthermore it is desirable that rotary or turning movement of the ring in the handle (in the direction of the length 120 of the wire) be minimized, and therefore the overlapped ends of the ring are extended to contact terminally with the inner surface of the tubular handle,—each terminal extending to the opposite side of the 125 130

tubular handle from that in which is formed the perforation through which said terminal is extended. In other words each of the overlapped terminals of the ring extends 5 diametrically across the bore of the handle to contact with the opposite side of the handle. The tubular form of the handle is particularly adapted to this arrangement in affording stops to limit the turning of 10 the ring and in housing the overlapped ends thereof.

Finally, in order to facilitate the application of the particular form of split ring indicated, and provide for the described over- 15 lapping of the ends thereof, in such relative positions that they may extend diametrically across the bore of the tubular handle and function as set forth, it has been found expedient to arrange the perforations in op- 20 posite sides of the handle in non-registering or non-aligned relation. The ends of the wire blank for each ring may thus be engaged respectively with the staggered or non-registering openings and when the ring 25 is squeezed or compressed to contract it, the terminals follow their proper parallel but non-aligned paths until checked, in suitable overlapping relation, by respective contact with the inner surfaces of opposite sides 30 of the tubular handle.

Thus, the substantially tubular construction of handle functions intimately in relation to the special form of split rings employed and is particularly advantageous by 35 reason of having a cross-sectional contour exceeding a semicircle and closely approaching the complete tubular form. As, however, there is an advantage in slightly separating the edges of the portion of the blank 40 forming the handles as a means of increasing the efficiency thereof as a gripping surface, I have elected to refer to the same as being "substantially tubular," to distinguish from those forms in which the concave or 45 hollow side of the handle is accessible for contact by a hand grasping the same, or in which the edges of the blank are exposed for contact with the hand instead of being drawn together and disposed in facing relation 50 as in the handle of the improved pin.

Attention is further called to a peculiarity in the construction of the blade or spoon which is formed as a part of the same blank with the rolled substantially tubular 55 handle or grasp and which is flattened out relatively to the handle or grip portion to represent a width in excess of the diameter of said handle portion; as shown clearly in Figures 1 and 6, said blade or spoon being 60 transversely dished or concaved throughout its length, and being alternately and progressively convexed and concaved longitudinally from the end of the rolled or handle portion toward the extremity of the blade 65 or spoon where it is reduced in width to form

a point for puncturing or penetrating the corn husk. The longitudinally convexed but transversely concaved portion of the blade or spoon immediately adjacent to the adjoining portion of the rolled handle af- 70 fords a bearing for the thumb of the hand by which the pin is manipulated, the end of the thumb resting upon this longitudinally convexed transversely concaved portion of the blade or spoon in the operation 75 of engaging the corn husk by means of the end of the blade, resisting to a point as indicated.

Moreover the blade or spoon throughout its length is longitudinally beaded or crimped, preferably on a center line or midway between the lateral edges thereof, the bead or crimp in the longitudinally convexed portion being directed upwardly or inwardly (that is toward the transversely 80 concaved surface of the blade or spoon) while the portion of the crimp or bead in the longitudinally concaved portion of the latter is directed rearwardly or outwardly, or in the opposite direction from that in the 85 longitudinally convexed portion, so that there is formed a continuous longitudinal reinforcing rib throughout the length of the blade or spoon, the portion of the bead at the convexed portion being disposed in 90 the transverse concavity of the blade while that of the longitudinally concaved portion is at the outer or convex surface of the longitudinally concaved portion of the blade, to afford the required strength and resist- 95 ance to distortion under the strains to which a device of this character is subjected in use.

Claims:—

1. A husking pin having a tubular handle or grip portion and connected blade or bowl, and a guide ring terminally engaged with side openings or perforations in said handle or grip portion, said openings or perforations being arranged in staggered relation.

2. A corn husker having a sheet metal 110 husking pin provided with a rolled tubular handle or grip portion and relatively broad blade or bowl, in combination with a leather shield or strap permanently secured to said handle or grip portion near the rear end 115 thereof, and a guide ring for said leather shield or strap consisting of a blank of wire terminally extended through lateral openings or perforations in said handle or grip portion and terminally housed in overlapping relation within the same.

3. A corn husker having a sheet metal 120 husking pin provided with a rolled tubular handle or grip portion and a relatively broad blade or bowl, in combination with 125 a shield or strap permanently secured to said handle or grip portion at one end of the latter and having a running engagement with said handle or grip portion near its forward end, said running engagement con- 130

- sisting of swinging rings engaged with transversely staggered side openings or perforations in the handle or grip portion and terminally housed within the latter in over-
lapping relation.
4. A corn husker having a husking pin provided with a tubular handle or grip portion, in combination with a strap disposed longitudinally of the pin, a rivet securing the strap to the handle or grip at the rear end of the latter and housed at its inner end within said handle, forward and intermediate guide rings embracing said strap to provide a running engagement therewith and having their terminals engaged with side openings or perforations in said tubular handle or grip portion, and a finger stall in engagement with said strap and having perforations for the reception of the forward guide ring.
5. A husking pin having a rolled handle or grip portion and a relatively flattened laterally spread blade or bowl which is forwardly curved adjacent to the end of the handle portion and is rearwardly curved toward its extremity and terminates in a forwardly directed point.
6. A husking pin constructed of a single blank of sheet metal and having a rolled approximately tubular handle or grip portion merging at one end into a blade or bowl which is transversely spread or flattened and is progressively curved forwardly and then rearwardly and terminates in a forwardly directed point.
7. A husking pin having a rolled handle or grip portion and a relatively flattened laterally spread blade or bowl which is forwardly curved adjacent to the end of the handle portion and is rearwardly curved toward its extremity and terminates in a forwardly directed point the blade or bowl being transversely concaved forwardly throughout its length.
8. A husking pin having a rolled handle or grip portion and a relatively flattened laterally spread blade or bowl which is forwardly curved adjacent to the end of the handle portion and is rearwardly curved toward its extremity and terminates in a forwardly directed point, the blade or bowl

being transversely concaved forwardly throughout its length, and being longitudinally traversed by an upstruck reinforcing web.

55

9. A husking pin having a rolled handle or grip portion and a relatively flattened laterally spread blade or bowl which is forwardly curved adjacent to the end of the handle portion and is rearwardly curved toward its extremity and terminates in a forwardly directed point, the blade or bowl being transversely concaved forwardly throughout its length, and being longitudinally traversed by an upstruck reinforcing web of which the portions traversing the forwardly and rearwardly curved areas are offset in opposite directions.

60

10. A husking pin having a rolled sheet metal substantially tubular handle or grip and hand engaging means including a split guide ring having its terminals disposed in parallel overlapping relations with the bore of the handle.

70

11. A husking pin having a rolled sheet metal substantially tubular handle or grip and hand engaging means including a split guide ring having its terminals engaged with side openings or perforations in said handle or grip portion and disposed within the bore of the latter in parallel overlapping relation.

75

12. A husking pin having a rolled sheet metal substantially tubular handle or grip and hand engaging means including a split guide ring having its terminals engaged with side openings or perforations in said handle and arranged in the bore thereof in overlapping relation with their terminals in engaging relation with the opposite sides of said bore.

85

13. A husking pin having a rolled sheet metal substantially tubular handle or grip and hand engaging means including a split guide ring terminally engaged with side openings or perforations in the handle or grip portion and disposed respectively in overlapping diametrically spanning relation with the bore of said handle or grip portion.

90

In testimony whereof I affix my signature.
EDWIN CLARK.
